UNITED STATES PATENT OFFICE

JESSE F. MADDEN, OF ROCKVILLE CENTER, NEW YORK

ASH RECEPTACLE

Application filed May 28, 1932. Serial No. 614,267.

Broadly speaking, my invention relates to an accessory for game tables, but more particularly to a combination device consisting of a stem cup or glass having its stem enlarged and provided with a recess for the reception of cigar ashes, or other waste material.

The device may be made of gold, silver, copper, glass, china or any other suitable material.

In playing various games at game tables, it is very common to accompany the games with beverages of different kinds, or with candy or cakes, and still more commonly with cigars. These ordinarily require drinking vessels for the beverages, receptacles for the candy or other confections, and ash trays for smokers, all of which takes up considerable room, and clutters up and crowds the game-table which according to custom is usually small, so that much crowding usually detracts from the pleasure of the game.

The object of the invention is to provide a single device for the centre of the table, which will serve all the players in common for the purposes above indicated, and thereby prevent the cluttered-up condition just referred to, while at the same time providing the centre of the table with an ornament or decoration suggestive of the friendliness and oneness of spirit so becoming to a social gathering.

One of the leading features of the invention may be briefly described as a drinking vessel having its stem enlarged and provided with a recess suitable for an ash tray.

The invention consists in certain novel features of construction and arrangement of parts, as will be hereinafter described and claimed, reference being had to the accompanying drawing, in which;

Fig. 1 is a sectional view of one form of my device.

Fig. 2 shows the device provided with a stem of modified form, and an opening of modified form leading into the ash recess.

Fig. 3 shows still another form of stem and opening leading into the interior there-

of; and also a slightly modified form of base.

Figs. 4 and 5 show still further modifications.

Fig. 6 is a top plan view of the style of base shown in Figure 3.

Fig. 7 shows one of my devices tipped high in the act of drinking without spilling any ashes from the ash receptacle in the stem of the glass.

Fig. 8 illustrates the device provided with a further modified form of opening for the ash receptacle; and,

Fig. 9 shows my idea adapted to a tea or coffee cup of late design.

Referring further to the drawing, the numeral 1 indicates the upper portion of my device, which is usually employed as a container for a beverage or a confection of some kind; and 2 indicates the enlarged or swollen stem; while 3 indicates the base.

The stem of the device has an internal recess 4 which serves as an ash receptacle. This recess and its functions are so similar in most forms of the device herein shown, that it is only deemed necessary to describe in full the recess as illustrated in Fig. 1 of the drawing, reference being had in the other figures only to the features different from the showing in Fig. 1. This ash recess or chamber 4 has an opening 5 leading out at one side, and in this opening the cigar or cigarette is entered, either to flick the ashes from the burning end thereof, or to hold the cigar when it is desired to lay it down for a time, to presently be taken up again. The opening is at the upper portion of the recess 4, so as to leave plenty of room in the bottom portion for ashes. The top wall or roof of the recess is inclined inwardly-and-downwardly from the top of the opening 5, so that when the device is inverted the ashes can be shaken out; but not till then. The lip 6 immediately underneath the opening 5 of the ash chamber, is clearly illustrated in Fig. 1, and constitutes an effective bar against the escape of ashes from the chamber when the device is in its normal position.

In Fig. 2 I have shown the stem of the 100

device formed in a diamond shape; and the opening leading into the ash chamber has a little, narrow, downward extension 5a at its lower side for the reception of cigarettes or diminutive cigars.

Fig. 3 shows a stem of still another external formation, and with its opening 5 provided at its lower side with two fingers 5b slightly spaced apart to form an opening 5c between them, and with the slightly wider openings 5d at either side of said fingers. The pedestal 3 of this form of the device is also provided with an elongated recess 3a and an integral raised block 3b which has a recess 3c. These recesses 3a and 3c are useful for holding pencils which the players may need for keeping the scores in some kinds of games, as for instance dominos. At times it may also be found convenient to lay cigarettes or matches in them, ready for the players if they desire them.

In the form of the device illustrated in Fig. 4, the ash receptacle is made round (spherical), and the lip at the lower side 25 of the opening 5 is turned inwardly, at its upper edge, as indicated at 7. This inwardly inclined portion 7 makes it impossible for the contents of the ash receptacle to be emptied out without turning the device upside down. It also serves as a shelf on which to lay a cigar or cigarette; and if desired, may be provided on its top side with a groove for laying the cigar or cigarette in.

The form of the device illustrated in Fig. 35 5, has the ash receptacle formed square, and has two openings leading thereto from opposite sides of the device. On the upper part of the ash receptacle in this form of the device, I provide two grooves 8, for the reception of pencils 9 to be used in keeping scores of the games when necessary.

In Fig. 6 the upper portion including the ash receptacle has been cut away in order to give an unobstructed top plan view of 45 the base of the device, as illustrated in Fig. 3, the object being to clearly show the block 3b and the recess 3c therein, and also the recess 3a on the opposite side of said base. In this recess 3a is shown a burnt match 3d, 50 which has been laid in the recess presumably to prevent soiling a dainty linen table spread.

Fig. 7 shows the device tilted as high as it would ever be tilted in taking a drink 55 from it, even when it was desired to drain the last drop from the cup; and yet, it will be seen that the ashes would not be spilt from the ash receptacle.

In Fig. 8, the opening leading into the ash receptacle is of a shape to grasp, as it were, any cigarette or cigar, regardless of whether it be large or small. Indeed, it is so constructed as to grip a match, if desired; and,

Fig. 9 shows my invention adapted to a

tea or coffee cup of very recent design, in which I have shown the base 10 turned slightly upward around its outer rim as indicated by 10a. The stem 11 of the cup is recessed for an ash receptacle, just as are the designs shown in the other figures of the drawing. This ash chamber may be provided with a small drawer 12 (shown in dotted lines), which will receive the ashes, so that the drawer can be withdrawn and the ashes emptied out without removing the cup from the table. The base 10 can also be used for ashes, cigar stubs, burnt matches, etc., when desired.

It will be seen that my device is of sturdy construction, and even when formed of glass will not be easily broken.

From what has already been said, it will be seen that in Figs. 2, 3, and 8, the openings leading into the ash receptacles are so constructed and arranged as to grasp or hold a cigar or cigarette in horizontal position when so desired.

In Fig. 4, the inturned lip 7 not only forms a shelf upon which a cigar may be laid, but at the same time forms a very effective means for preventing the accidental escape of ashes from the ash receptacle.

Any of the forms of openings shown will permit cigars or cigarettes to be placed therein with the inner ends of the cigars resting on the bottom of the ash receptacle if desired.

The ashes from a cigar may be flicked in the ash receptacle in the usual way, or the cigar may be stuck into the receptacle till the lighted end abuts against the rear wall thereof, and thus completely removes the ashes.

The operation of the device is so obvious that further description thereof is unnecessary.

The forms of the device shown in Figs. 1, 4, 7, and 8, are used when the device is to be made of metals, especially the precious metals. These forms lend themselves readily to burnishing and polishing processes. When the device is to be made of gold, or silver, or burnished copper, for the drawing rooms of the rich, or for loving cups, or for gift purposes, they are intended to be handsomely engraved. For persons of a different taste, who prefer cut glass to the precious metals, the forms shown in Figs. 2 and 3 are employed; and fancy figures are formed on the bowl of the glass.

For a very sturdy construction, the form of the device shown in Fig. 5 (with two openings leading into the ash tray), is used.

Any of the forms shown may, of course, be made of common glass, aluminum, brass, etc., as well as of more costly materials, to suit the varying tastes and purses of customers.

The form of the device shown in Fig. 9,

is well suited for those who desire the devices in gold, silver, or plated ware, in a unique design homelike and tasty, and very suggestive of sociability and good fellowship.

5 For persons who only desire a good ash tray, it is thought this device is greatly preferable to the ordinary ash trays now in common use, and should supplant them on the market.

10 Where only an ash tray is desired, the upper part of the device can be used for matches; or, if the users prefer, the upper part can be used for ashes, and the ash receptacle can be used for matches, in which case 15 the burnt matches can also be deposited in the upper part with the ashes.

As a new article of manufacture, simply designed to take the place of an ordinary ash tray, the form of the device illustrated in 20 Fig. 9 greatly commends itself, since its saucer-like base may also be used as a place for depositing ashes, cigar stubs, etc.

Hence, it will be seen that while the form 25 of the device illustrated in Fig. 9, is very handy and tasty and appropriate when something extra dainty and costly is desired, it is equally well suited to be made of inexpensive material to take the place of the ordinary ash tray, and be greatly preferable 30 thereto.

In this form of the device it will be seen that the opening leading into the ash receptacle is immediately under the handle of the device, so that when the device is taken hold 35 of by the handle to take a drink from the cup, it will naturally be tilted in a direction at right angles to the plane of the handle so that there will be no danger of ashes being 40 emptied out of the ash receptacle in tilting the cup to take a drink therefrom, since the device has to be tilted toward said opening in order to dump the ashes from the ash receptacle.

In this connection it may also be observed 45 that in the other forms of the device, the user naturally takes hold of the stem, and he can always do that in a way to close the opening; but even if he takes hold of the stem carelessly his hand is apt to close the opening leading into the ash receptacle, because that opening is on the side of the swollen stem, and in taking hold of this stem the hand ordinarily largely surrounds it.

An additional advantage of having the 55 shelf 7 turned inwardly, as shown in Fig. 4, is that the shelf cannot in any way prevent the hand of the user from effectually covering the side opening 5 of the ash receptacle when the same is grasped by the user to take 60 a drink from the cup.

At any rate, there is only one position in which the cup, in most forms of the device, can be tilted in order to dump ashes from it at all, even when it is desired to do so; and 65 it is always possible and easy to tip the cup

in a way not to empty the ashes from the ash receptacle.

And finally, the cup ordinarily is only intended to be used to take a sip or two therefrom at a time, and is not sufficiently 70 tilted to empty ashes therefrom, no matter what direction it is tilted in. So that the arrangement is practically such that in ordinary use there will be little danger of wasting any ashes from the ash receptacle. 75

Having now described my invention, and shown a few of the forms in which it may be embodied, what I claim as new and desire to secure by Letters Patent is;—

1. An article of the character described 80 having a comparatively large upper section for a beverage receptacle; an intermediate section of reduced size and internally recessed for an ash receptacle; and a broad base section for normally supporting the 85 device in a vertical position, said upper section being made progressively larger from its bottom to its top and open at its top to form said section into a drinking cup from which the contents will be drained before 90 the article is brought to the horizontal position, said recess of the intermediate section opening laterally outward through the wall of said section at the upper end of said recess and being closed at the lower end 95 thereof; whereby when the device is moderately tipped in drinking therefrom, the ashes will not be dumped from the ash receptacle; and whereby the ashes can never be dumped therefrom except by tilting the device more than is ordinarily done in drinking 100 from the cup.

2. An article of the character described 105 formed of a single piece of material non-permeable to fluids and having three sections all of circular formation, an upper section, an intermediate section, and a lower base or section, the device being designed to simultaneously hold fluid material and dry material separated from each other, the upper section being formed into a drinking vessel made progressively larger from its bottom to its top and open at its top, the intermediate section being of smaller diameter than either of the other sections, whereby to 110 adapt it to be grasped by the hand of the user, said drinking vessel having the upwardly-flared formation described in order to adapt it to be drained of its contents before it is tilted to the horizontal, said intermediate section having therein a recess opening laterally outward through the wall of the intermediate section at the upper end of the recess and being closed at the lower end thereof, whereby when the device is tipped 115 in drinking therefrom, the ashes will not be dumped from the ash receptacle.

3. An article of the character described 120 having its upper end formed into an upwardly flared drinking cup; an intermediate 125

section of reduced diameter for an ash receptacle; and a base section for supporting the device in a vertical position, the drinking cup being flared upwardly as described 5 to adapt it to be drained of its contents before it reaches the horizontal when tipped to take a drink therefrom, the intermediate section having a recess therein opening laterally outward through the wall of said section 10 at the upper portion of the recess; whereby the drinking vessel at the top of the device may be tipped in any direction sufficiently to drain it of its contents without dumping ashes from the ash receptacle; and 15 whereby the ashes can be dumped from the ash receptacle only by tipping the device beyond the horizontal in the direction of the side opening of the intermediate section.

4. An article of the character described 20 having an upper section, an intermediate section, and a base section, the upper section being formed into a drinking cup opening upwardly, the intermediate section being recessed to form an ash receptacle, said recess 25 of the intermediate section having an opening leading out laterally through the wall of said section at the upper portion of the recess, said opening having at its lower side an inwardly-turned lip to prevent the escape 30 of ashes from the ash receptacle when the cup is tilted excessively in the direction of the outlet opening of the intermediate section.

5. An article of the character described 35 with an upper cup-shaped section having a handle on one side thereof; an intermediate section with a recess therein for an ash receptacle; and a saucer-shaped base, said recess in the intermediate section having an 40 opening leading out through the wall of said section at the upper end of said recess and at a point underneath the handle of the cup, whereby when the cup is tipped in drinking therefrom, it will not be tipped toward said 45

outlet opening of the ash receptacle in the intermediate section, and therefore ashes will not be dumped from the ash receptacle in the ordinary use of the cup for drinking purposes. 70

6. An article of the character described having an upper section, an intermediate section, and a base section, the upper section being formed into a drinking cup open at the top, the intermediate section being of a reduced size adapted to be easily grasped by the hand of the user, and recessed to form an ash receptacle, said recess having an opening leading out laterally through the wall of said section at the upper portion of said recess, said opening having at its lower side an inwardly-turned lip to prevent the escape of ashes from said opening when the drinking cup is tilted in the direction of said recess in taking a drink from the cup, said inwardly-turned lip also serving as a cigar support turned inwardly where it will not be exposed to knocks causing breakage of the same, and also where it will present no obstruction to the hand of the user in readily grasping said intermediate section. 85

7. An article of the character described 90 having its upper end formed into an upwardly-flared drinking cup; an intermediate section of spherical formation and internally recessed to form an ash receptacle; and a base section for supporting the device in a vertical position, the intermediate section being of reduced diameter and having its recess opening laterally outward through the wall of said section at the upper portion of the recess, said opening having at its lower side an inwardly-turned lip to prevent the accidental escape of ashes from said internal recess, when the drinking cup chances to be tipped in the direction of said outlet opening. 95 100 105
